UNITED STATES PATENT OFFICE.

JAMES G. BLUNT, OF SCHENECTADY, NEW YORK.

TRUCK-CENTERING DEVICE.

Application filed May 4, 1923. Serial No. 636,568.

To all whom it may concern:

Be it known that I, JAMES G. BLUNT, a citizen of the United States, and a resident of Schenectady, in the county of Schenectady and State of New York, have invented a certain new and useful Improvement in Truck-Centering Devices, of which improvement the following is a specification.

My invention relates to centering devices for railroad trucks, of the type in which rollers are applied between reversely inclined surfaces, for exerting a resistance to the lateral displacement of one roller seat, relatively to the other, when passing over a curved portion of the track, and producing a tendency for the rollers to return to the bottom of the inclines, in order to bring the parts back to the normal central position when returning to a straight portion of the track.

With this roller type of centering device, as heretofore applied in practice, it has been found that the rollers have a tendency to slide without turning, thereby becoming flattened, and defeating the purpose for which they were intended, and one of the objects of my invention, is to provide means for effecting a positive and simultaneous rolling movement of the rollers, whenever the roller seats are subjected to relative lateral displacement. Another object is to prevent any longitudinal displacement of the rollers, with respect to their paths and to enclose and protect the moving parts from the access of dust and grit, and ensure the maintenance, in correct alignment and operative relation, of the members of a truck centering mechanism of the type to which my invention relates.

The improvement claimed is hereinafter fully set forth:

In the accompanying drawings: Figure 1 is a plan view of a locomotive engine trailing truck, embodying my invention; Fig. 2, a side view, in elevation, of the same; Fig. 3, a rear view; Fig. 4, a side view, in elevation, of the upper roller seat; Fig. 5, an inverted plan view of the same; Fig. 6, a similar view of the lower roller seat; Fig. 7, a side view, in elevation, of the same; Fig. 8, a plan view of the roller yoke; Fig. 9, a side view of the same; Fig. 10, an end view, in elevation, of a roller; Fig. 11, a plan view of the same; Fig. 12, a plan view of the key locating the roller seat on the top

of the truck box; Fig. 13, a side view of the same; Fig. 14, a plan view of the assembled spring seat and roller seat; Fig. 15, a longitudinal section through the roller seats; Fig. 16, a transverse section through the spring seat and upper roller seat; and, Fig. 17, a transverse section through a spring seat plate.

My invention is herein exemplified as applied in a two wheeled locomotive engine trailing truck, of the well known "Cole" type, in which an axle, 1, on which a pair of wheels, 2, is secured, is fitted to rotate in journal boxes, 3, which are mounted, with the capacity of relative movement, in the side members, 4, of the truck frame, said members being formed integral with forwardly and inwardly extending radius bar arms, 4^a, and a rear transverse bar, 4^b. The truck frame is, in the usual manner, pivotally connected to the main frame of the locomotive by a radius bar pin, passing through an eye, 4^c, located in the longitudinal central plane of the truck, at the forward extremity of the radius bar arms.

In the practice of my invention, there is mounted on each of the journal boxes, 3, a lower roller seat, 5, on each side of the upper face of which there are formed two racks, 5^a, each rack being inclined, downwardly and upwardly, alternately from the middle transverse plane of the roller, and an upper roller seat, 6, having similarly located racks, 6^a, inclined, upwardly and downwardly, alternately, is supported on each of the lower roller seats, 5, through the intercession of two rollers, 7, each of which is fixed on a pin, 7^b, and has formed on its ends, pinions, 7^a, which engage the racks of the upper and lower roller seats, 6 and 5. The inclination of the racks is predetermined to present the desired degree of centering effort or lateral resistance, and in normal position, on a tangent track, the axes of the rollers are directly in line with the intersection of the reversed inclines of the racks as shown in Fig. 15.

In order to ensure the operation of the rollers in unison, and the maintenance of their axes in normal relation one with the other, as well as to protect the teeth from the access of dust and grit, there is provided, for each pair of roller seats, a roller yoke, 8, which is in the form of an open bottomed casing, enclosing the rollers, and having

bearings, 8^a, on its sides, for the pins, 7^b, of the rollers. Downwardly projecting flanges, 8^b, on the ends of the roller yokes protect the lower roller seat from deposit of dirt under the full amount of roller travel.

The proper location of the lower roller seats, 5, on the journal boxes, 3, is effected and maintained by keys, 9, which engage channels in the journal boxes, formed on lines passing through the middle planes of the spring seats, 3^a, of the journal boxes, and through the axial line of the radius bar pin eye, 4^c, said keys also engaging channels, 5^b, in the bottoms of the lower roller seats, 5, 15 cut at right angles to the lines of roller travel. The direction of roller travel is thereby rendered essentially normal to the axial line of the swivelling of the truck, which is that of the radius bar pin eye, 4^c. 20 Recesses, 6^b, extending parallel with the longitudinal central plane of the locomotive, are formed in the tops of the upper roller seats, 6, for the reception of square plates, 10, in which dowels, 3^b, on the bottoms of the 25 spring seats, 3^a, are fitted. Circular grooves, 10^a, for carrying lubricant, are formed in the bottoms of the plates, 10, and said plates have the capacity of movement longitudinally, so as to automatically maintain the 30 fixed location of the spring seats, while permitting the upper roller seats to travel in a path concentric with the radius bar pin eye, 4^c. As shown in Fig. 17, the plate, 10, is also bevelled at its top, at its front and rear 35 sides, to permit the rise and fall of the truck, due to irregularities in the track, with the radius bar pin acting as the connection for swivelling movements of the truck.

The spring seats, 3^a, constitute the connecting links, between the truck frame and the floating yokes, 11, which, by reasons of articulations made by pins passing through lugs, 11^a, on the floating yokes, compensate for all fluctuations of the truck frame, relatively to the main frame of the locomotive.

I claim as my invention and desire to secure by Letters Patent:

1. In a radial railroad truck, the combination of a truck frame; journal boxes, fitted 50 therein; lower roller seats, mounted on said journal boxes and having lateral racks, each oppositely inclined in the direction of its length; keys, engaging channels in the journal boxes and lower roller seats, inclined in 55 planes intersecting in the axis of the radius bar pin; upper roller seats, having lateral racks, each oppositely inclined in the direction of its length; and rollers, interposed between the roller seats and carrying pinions, 60 engaging the racks thereof.

2. In a radial railroad truck, the combination of a truck frame; journal boxes, fitted 65 therein; oppositely facing roller seats, supported on said journal boxes, and having lateral double inclined racks; rollers, inter-

posed between the roller seats and carrying pinions engaging the racks thereof; keys, engaging channels in the journal boxes and adjacent roller seats and inclined in planes, intersecting in the axis of the radius bar pin; and spring seats, supported on the upper roller seats.

3. In a radial railroad truck, the combination of a truck frame; journal boxes, fitted 75 therein; oppositely facing roller seats, supported on said journal boxes and having lateral double inclined racks; rollers, interposed between the roller seats and carrying pinions engaging the racks thereof; keys, engaging channels in the journal boxes and adjacent roller seats and inclined in planes intersecting in the axis of the radius bar pin; spring seats, supported on the upper roller seats; and floating yokes, connected to the spring 80 seats and adapted to be coupled to the main frame of the vehicle on which the truck is 85 installed.

4. In a radial railroad truck, the combination of a truck frame; journal boxes, fitted 90 therein; oppositely facing roller seats, supported on said journal boxes and having lateral double inclined racks; rollers, interposed between the roller seats and carrying pinions engaging the racks thereof; keys, engaging channels in the journal boxes and adjacent roller seats and inclined in planes intersecting in the axis of the radius bar pin; spring seats, supported on the upper roller seats; and means for permitting movement of the upper roller seats, relatively to the spring seats.

5. In a radial railroad truck, the combination of a truck frame; journal boxes, fitted 95 therein; oppositely facing roller seats, supported on said journal boxes and having lateral double inclined racks; rollers, interposed between the roller seats and carrying pinions engaging the racks thereof; keys, engaging channels in the journal boxes and adjacent roller seats and inclined in planes intersecting in the axis of the radius bar pin; spring seats, supported on the upper roller seats; and plates, connected to the spring seats and engaging channels in the upper roller seats.

6. In a centering device for radial trucks, the combination of an upper roller seat; a lower roller seat, each of said seats having lateral racks, each oppositely inclined in the direction of its length; rollers, interposed between said seats and carrying pinions engaging the racks thereof; and open bottomed roller yokes, encasing the racks and pinions.

7. In a centering device for radial trucks, the combination of an upper roller seat; a lower roller seat, each of said seats having lateral racks, each oppositely inclined in the direction of its length; rollers, interposed between said seats and carrying pin-

ions engaging the racks thereof; and open bottomed roller yokes, encasing the racks and pinions, and having lateral bearings for the rollers.

5 8. In a centering device for radial trucks, the combination of an upper roller seat; a lower roller seat, each of said seats having lateral racks, each oppositely inclined in the direction of its length; rollers, inter-

posed between said seats and carrying pin-¹⁰
ions engaging the racks thereof; and open bottomed roller yokes, encasing the racks and pinions and having flanges projecting downwardly from their ends.
